UNITED STATES PATENT OFFICE

EUGENE A. NAHM, OF CHICAGO, ILLINOIS

SLOT MACHINE AND ATTACHMENT THEREFOR

Application filed August 6, 1928. Serial No. 297,879.

This invention relates in general to coin slot machines and has more particular reference to slot machines of the type used for receiving coins and slugs.

5 A principal object of the invention is in the provision of means for receiving coins and slugs of a certain size and excluding those of a different or larger size.

10 A further object of the invention is in the provision of a removable attachment for receiving optionally slugs of different sizes, excluding those of larger dimensions.

15 A special object of the invention is in the provision of an attachment for fare and fee 55 registering slot machines which may be applied to conventional devices of this kind for accurately registering fares and fees and tending to prevent falsification of the fare and fee returns.

20 A still further object of the invention is in the provision of a number of removable coin slot attachments, each adapted to receive optionally two or more slugs of different sizes, which may be interchanged for 60 varying the rate of fare or fee which the slot machine is intended to receive.

25 Other objects will appear hereinafter, the drawing illustrating a preferred embodiment of the invention.

30 In the drawings, Fig. 1 is an elevational view of a coin slot machine showing this attachment applied thereto; Fig. 2 is a side elevational view of the structure of Fig. 1; Fig. 3 is an end elevation of a coin slot mechanism and this attachment therefor; Fig. 4 is a perspective of the attachment with one 65 of the plates removed; Fig. 5 is a fragmentary perspective of that part of the coin slot mechanism which receives and cooperates

35 with this removable attachment; Fig. 6 is a sectional view of the removable attachment; Figs. 7, 8, 9, 10, 11, and 12 are face and elevational views of special tokens or slugs used in connection with the present invention.

40 In places of amusement such as theaters, halls and shows of various kinds, it is the usual practice to sell tickets at a booth which are subsequently tendered by the purchaser at the entrance of the amusement place where 70 they are deposited or received by an attend-

ant to be deposited in a suitable receptacle.

In selling and depositing paper tickets, it is sometimes not very difficult to withdraw or withhold some of the tickets tendered, returning them to the cashier for resale, the 75 money received for these tickets being dishonestly shared among those party to the transaction.

The present invention is intended to provide a substitute for tickets by providing 80 tokens or slugs of predetermined value. These tokens or slugs may be operative to ring a bell or cause other visible or audible signs or sounds, indicating that a certain fare 85 has been paid.

In the present invention a coin chute is provided which will exclude all United States coins and will only admit tokens of two species, one of wide face diameter but thin, and the other comparatively thick and of 90 smaller face diameter. The purpose of this is to enable the management of the amusement place to provide means for receiving and registering two different fares, as for example a half fare for children and the usual 95 full fare for adults, also to provide a correct check of admission fees received even though the rates of admission are changed at certain hours of the day. A coin registering mechanism in which a bell or other signalling 100 means gives notice that a token of the proper value has been inserted not only indicates to the patron and the owner of the place of amusement that the fare or fee has been received but it also provides to a certain extent 105 a remedy against collusion between the door tender and the cashier.

Referring more particularly to the drawings, a coin receiving mechanism A has a casing 15 slidably mounted on rods 16 and 17 secured at their ends in flanges 18 and 19 of a plate 20 which in turn is attached by screw bolts 21 to a double plate 22 having a bracket 23. The bracket provides a mounting for a member 24 pivoted on a bar 25 and resiliently 110 actuated by a spring 26. The member 24 contacts with a bar 27 pivoted in lugs 28 extending from the slidable casing 15. On another bracket 30 attached to the lower end of plate 22, a rocking member 31 is pivoted having 115

binding posts 32 and 33 for attachment to a suitable source of electric energy for the actuation of the coin receiving mechanism.

The coin receiving mechanism forms no part of the present invention, being merely described to provide an operative connection for the coin slot attachment B which is connected to the upper part of plate 22. The plate 22 is provided with adjacent channels 34, 35 of different dimensions which are adapted to register with similar channels in the removable attachment B, those in the plate 22, however, being of a size to receive the largest slugs which are admitted by any 10 of a number of removable attachments B which are applied to the coin mechanism A.

Each attachment B comprises two plates 36 and 37 riveted or otherwise suitably joined together having a pair of pins 38, 39 at opposite ends of a slot formed by two downwardly projecting ends of the plates, the slot being adapted to receive the upper end of the double plate 22, the pins 38, 39 serving as guides to secure the attachment B to the 25 plate 22 which is provided on its upper end with reduced shoulders 43, 44 for closely receiving the attachment.

As shown in Figures 4 and 6, plate 37 has a central recess or channel 40 having shoulders 30 41, 42 which provide means for receiving two tokens or slugs, one of a larger face diameter than the other; and the other of greater thickness than the first one.

The inner wall or channel of the double 35 plate 22, as shown more clearly in Figure 5, is also provided with a central channel 34 having side shoulders 46, 47 whereby a wider channel 35 is formed so that when an attachment B is fitted at the top of the plate 22 the channels of the attachment and plate will 40 register for the proper reception of the special tokens or slugs.

At the top of each attachment B is a 45 curved and bevelled coin receiving recess 50 which enables the purchaser or an attendant to insert the coins or slugs quickly and accurately into the coin chute C. As pointed out, each attachment will receive a coin comparatively thick but of smaller diameter, and a larger one of a comparatively wide face diameter but relatively thin. The chute just described is intended to exclude all United States coins or coins of other countries as by 50 graduating the sizes of the tokens and correspondingly varying the sizes of the attachments. One coin receiving mechanism is sufficient to accommodate a number of different admission fees or rates of fare, and these 55 attachments eliminate the possibility of receiving a low rate period token during the high rate period.

The tokens vary in size for different values, the larger tokens, as shown by Figures 10, 11 60 and 12, being larger for each smaller value

than it is for larger values, and the small tokens, as shown by Figures 7, 8 and 9, varying in the same manner. The amount of variation between the tokens is very slight, being usually but a few hundredths of an inch 70 and not apparent by inspection of these figures without actually applying a scale to them. By providing a separate adapter for the one large token, as shown in Figures 10, 11 and 12 and for one small token as shown by Figures 9, 8 and 7, a convenient means is afforded for receiving half fare and full fare at the same time. By varying these adapters the tokens received thereby are also varied; for example, the full fare in an amusement 80 place is fifty cents up to a certain time of day and a dollar thereafter, by making a one dollar adapter for tokens of smaller diameter, the fifty cent tokens cannot be received through the one dollar adapter. 85

There may be times when it is desirable to receive United States or other currency, and at such time the channels of the adapter are varied in size accordingly. Generally speaking the removable attachment of the present invention and the method described is particularly valuable when it is formed to admit tokens or slugs varying in size but reversely in accordance with their values as 90 herein described and illustrated. 95

It is obvious that various changes may be made in the construction and arrangement of the parts without departing from the spirit and scope of the invention. For example, each attachment may have channels for a plurality of slugs graduated in diameter and thickness, and slugs may be made with projections or depressions and the channels formed accordingly so that tokens of more 100 than two different values may be received optionally. 105

I claim:

1. In combination with a coin slot mechanism, of a series of interchangeable attachments therefor, each attachment having a channel shaped to receive optionally different sized slugs, and the channels of the series being relatively graduated in size reversely to the value of the slugs. 110

2. The combination with a coin slot mechanism, of a plurality of separate but interchangeable attachments therefor, each attachment having a slug opening and the openings of the attachments being relatively graduated in size reversely to the value of the slugs to be received, whereby a slug of lower value cannot be inserted in an attachment intended for a slug of higher value. 120

3. A device of the kind described, comprising a coin slot mechanism in combination with a removable attachment therefor, said coin slot mechanism having a part formed to receive said removable attachment, channels in said part registering with channels in said 125 130

attachment, said channels being of sizes to optionally receive differently sized slugs insertable within said channels.

4. A device of the kind described comprising, in combination, a coin slot mechanism having an upper wall recessed to provide adjoining channels; an attachment removably secured to said upper wall, said attachment having channels registering with the channels of the said wall, whereby means are provided to receive slugs of different sizes, while excluding larger and thicker coins and slugs.

5. A two-value admission and prepayment system for tokens representing values graduated in size reversely to the values of the tokens, comprising a plurality of removable and interchangeable coin slot attachments, each attachment having a single slot shaped to receive optionally two different sized tokens, one representing a full fee or admission charge and the other a partial fee or admission charge, and the different attachments having relatively different shaped slots whereby the admission fees at different times 20 of the day and for different days may be varied.

6. A two-value admission system for tokens representing values, comprising a fare box having a transmission slot, and a plurality of 30 token receiving attachments therefor which are interchangeable and have relatively differently shaped slots whereby the admission fees at different times of the day and for different days may be varied.

35 7. A two-value admission system in accordance with claim 6 in which each of the interchangeable attachments has slots varying relatively in size, reversely to the indicated values of the tokens to be received, whereby 40 tokens of lower value cannot be inserted in slots intended for tokens of larger value.
